UNITED STATES PATENT OFFICE.

FREDERICK C. CLEMENT, OF PHILADELPHIA, PENNSYLVANIA.

RECEPTACLE CLOSURE.

Application filed February 5, 1926. Serial No. 86,119.

This invention relates to closures more particularly useful with food or beverage receptacles, such, for example, as bottles or flasks, decanters, jars, etc.

5 The main purpose of my invention is to secure in connection with closures of the type referred to, capacity for easy placement and removal without sacrifice of effective fluid-tightness against contamination of 10 the receptacle contents due to extraneous conditions, or evaporation from within.

A further object is to attain the foregoing advantages in a closure that is proof against germination, easily cleaned, and capable of 15 readily withstanding sterilization without injurious effects.

With reference to the drawings, Fig. I is 20 an elevation of a thermo-insulated decanter flask with the neck partly broken away and in section to show the manner in which a closure of my invention is applied.

Fig. II is an inverted plan view of the closure on a somewhat larger scale; and,

Fig. III is an axial sectional view of the 25 same taken as indicated by the arrows III-III in Fig. II.

In the embodiment chosen for illustration herein, my improved closure has the form of a stopper characterized by a longitudinally divided tubular body portion 5 which is 30 adapted to engage within the neck of the flask, a cap piece 6 affording a circumferential flange to overhang the mouth of said flask, and a grasp member or finger knob 7; 35 all of which are constructed of non-corrosive material, preferably metal, and arranged in coaxial relation as shown. The body portion 5 is fashioned from a single strip of springy sheet metal to slightly tapered cylindric configuration, with the lateral ends of the sheet in overlapping contact longitudinally, as indicated at 8 in Figs. I and II. By virtue of this construction, the body portion 5 is rendered circumferentially extensible for capacity to adapt itself to the flask outlet with a snug though yielding fit.

40 As a means to augment the contractile resistivity of the body portion 5—particularly at its top—so that the mouth of the flask is engaged with greater firmness, I employ a supplemental element 9, conveniently formed from a piece of spring wire with a central eye 10 and symmetrically disposed flanking arms 11. These arms 11 are complementarily rounded or bowed to coincide with the interior curvature of the body portion 5, and

are permanently secured to the latter flush with its upper edge by welding or soldering.

The cap piece 6 may be a stamped sheet metal disk with an axial aperture for passage of a screw 12 that engages through the central eye 10 of the element 9 and takes axially into the finger knob 7, thereby securing the component parts of the device together. It is to be particularly noted that 60 the element 9 functions as a coupling between the body portion 5 and the other parts of the closure, the connection being such that the entire surface of said body portion is adapted for resistive compression circumferentially. For greater security after assembling, the head of the screw 12, and the eye 10 of the element 9 are soldered or welded to the contiguous central portion of 65 the cap piece 6.

In applying the closure, it will be apparent that the free lower end of the body portion 5 yields readily under its inherent springiness as it is introduced into the neck of the flask but with continued advance of 70 said body portion, the influence of the spring element 9 progressively effective in increasing the resistivity to circumferential contraction. Consequently, when the closure finally comes to a stop with the cap piece 6 75 resting open or over the flask mouth, a very firm and substantially fluid-tight engagement obtains between the circumferential surface of the body portion 5 and the interior surface of the flask outlet neck.

Having thus described my invention, I 80 claim:

1. A receptacle closure comprising a longitudinally-divided tubular body member of springy material, a grasp member, and a resilient member medially connected co-axially of the grasp member having opposed complementary-shaped free arms that are rigidly secured to the body member at its top, whereby freedom for gradual increasing resistivity 85 to contraction is afforded the body member 90 when engaging the wall of the receptacle opening.

2. A receptacle closure comprising a longitudinally-divided tubular body portion, 105 a grasp member, and an element rigidly secured to the grasp member, said element embedding opposed complementary curved spring arms rigidly attached at their free ends to the top of said body portion with 110 capacity to permit circumferential expansion of said body portion and—contrari-

wise—to gradually augment the resistivity to contraction in engaging the wall of the receptacle opening.

3. A receptacle closure comprising a longitudinally-divided tapering-tubular body portion; a grasp member; and an element having a central eye secured axially to the grasp member with complementary bowed spring arms permanently attached flush with

10 the upper edge of the body portion from

within; said element thereby permitting yielding circumferential extensibility of said body portion and, contrariwise, gradually augmenting the resistivity to contraction in engaging the wall of the receptacle 15 opening.

In testimony whereof, I have hereunto signed my name at Philadelphia, Pennsylvania, this 1st day of February, 1926.

FREDERICK C. CLEMENT.
